UNITED STATES PATENT OFFICE.

FRANK H. OSBORN, OF SACRAMENTO, CALIFORNIA.

PAINT-BRUSH.

1,130,759.

Specification of Letters Patent.

Patented Mar. 9, 1916.

Application filed April 21, 1914. Serial No. 466,472.

To all whom it may concern:

Be it known that I, FRANK H. OSBORN, a citizen of the United States, residing at Sacramento, in the county of Sacramento and State of California, have invented a new and useful Paint-Brush, of which the following is a specification.

The device forming the subject matter of this application is a paint brush and one object of the present invention is to provide an implement of this type having a drip cup, adapted to receive paint or any other substance which is applied by the brush, when the bristles of the brush are upwardly disposed, the device being adapted, primarily, for use upon overhead work.

Another object of the invention is to provide novel means whereby the paint or other material which is received in the drip cup may be fed readily onto the bristles of the brush when the brush is inverted so that the handle is uppermost.

With the above and other objects in view which will appear as the description proceeds the invention resides in the combination and arrangement of parts and in the details of construction hereinafter described and claimed it being understood that changes in the precise embodiment of the invention herein disclosed can be made within the scope of what is claimed without departing from the spirit of the invention.

In the accompanying drawing: Figure 1 shows the invention in elevation; Fig. 2 is a longitudinal section.

In the accompanying drawings there is shown a paint brush which may be of any desired construction, the same being depicted as comprising a handle 1, bristles 2 and a ferrule 3 which serves to hold the bristles assembled with the handle.

In carrying out the present invention there is provided a receptacle 4 of tubular form, the same preferably being fashioned from metal and being reduced to form a neck 5 which engages the ferrule 3 closely, or engages the handle 1 if the ferrule is slightly shorter than shown in the drawings. Resilient fingers 6 preferably made of metal are secured at their upper ends to the inner face of the receptacle 4 and are curved so

that their free ends lie adjacent the bristles 2. These fingers 6 serve as feeding fingers, controlling the action of the paint as the latter flows from the receptacle 4 onto the bristles 2 when the brush is employed with the handle 1 uppermost. The receptacle 4 is equipped at one side with a hook 7 adapted to engage over the edge of a paint pail (not shown).

As will be understood readily, when the brush is inverted so that the bristles 2 stand uppermost, the paint, instead of dripping, will be collected by the receptacle 4. Thereafter, when the brush is inverted so that the bristles 2 are downwardly disposed, the paint will be returned to the bristles and be evenly distributed by the feeding fingers 6. It is desirable that the brush be equipped with the feeding fingers for the reason that when the brush is turned downward, the fingers cause the paint to flow back onto the bristles of the brush, whereas, if there were no fingers, the paint would simply run over the edge of the cup and drip down.

Having thus described the invention, what is claimed is:

In a device of the class described, a brush, including an applying element; a receptacle surrounding the applying element and so spaced peripherally therefrom to define a drip compartment; and feeding fingers secured at their inner ends to the receptacle and prolonged transversely of the compartment to dispose their outer ends adjacent to the applying element, the fingers being spaced to permit the material applied by the brush to pass between the fingers from the applying element into the compartment when the applying element projects upwardly, and to permit air to enter the compartment when the applying element projects downwardly, the fingers being disposed in a continuous series around the applying element.

In testimony that I claim the foregoing as my own, I have hereto affixed my signature in the presence of two witnesses.

FRANK H. OSBORN
